UNITED STATES PATENT OFFICE

106,926

DESIGN FOR A DRESS ENSEMBLE

Margaret Michelson, New York, N. Y.

Application October 6, 1937, Serial No. 71,993

Term of patent 3½ years

To all whom it may concern:

Be it known that I, Margaret Michelson, a citizen of the United States of America, residing in New York city, in the Borough of Manhattan, county and State of New York, have invented a new, original, and ornamental Design for a Dress Ensemble, of which the following is a specification, reference being had to the accompanying drawing, forming part thereof, wherein,

My design is characterized by the sequin studded stripes on the front and back portions of the dress section, as well as the front and back portions of the jacket.

I claim:

The ornamental design for a dress ensemble, substantially as shown, and described.

MARGARET MICHELSON.
